ATTORNEY.

UNITED STATES PATENT OFFICE

WILLIAM J. VERNIER AND LAURENCE H. COOLEY, OF PORTSMOUTH, OHIO

LAST

Application filed March 8, 1929. Serial No. 345,343.

This invention relates to a method of and apparatus for attaching wood heels to shoes and has for one of its objects to provide, in a manner as hereinafter set forth, a method and apparatus of such class whereby wood heels may be secured to shoes with a uniformly close fit, thereby eliminating the likelihood of the heels becoming loose either before or after the shoes leave the factory.

10 Another object of the invention is to provide a method and apparatus of the class aforesaid, by means of which the working time necessary for attaching heels according to other known methods may be materially reduced with a corresponding reduction in the expense incident to the heel attaching operation.

Another object of the invention is to provide a method and apparatus of the class 20 aforesaid whereby waste, such as is caused by broken heels and lasts, may be materially reduced.

Another object of the invention is to provide a method and apparatus of the class 25 aforesaid, which requires a minimum outlay for machinery and the like in carrying out the heel attaching operation.

Other objects and advantages of the invention will be apparent during the course of 30 the following description.

In the accompanying drawings wherein like numerals are employed to designate like parts throughout the same:

Figure 1 is a fragmentary vertical section 35 of a shoe, showing our improved last in association therewith.

Figure 2 is a top plan of the last.

Figure 3 is a bottom plan of the last.

Figure 4 is a top plan of our insole plate 40 shown in position on an insole.

Figure 5 is a perspective view of the last thimble.

Referring to the drawings in detail, the 45 numeral 1 designates the heel portion of a last formed with an opening 2 extending vertically therethrough. Extending partially through the opening 2 from the upper end thereof is a thimble 3 for connecting the last with a last jack, not shown. Spaced from the bottom thereof, the wall of the opening

2 is formed with a shoulder 4 against which the lower end of the thimble is seated and adjacent the upper end of the opening, the wall thereof is formed with a similar shoulder 5 against which a flange 6 formed on the upper end of the thimble 3 is seated. The upper face of the flange 6 is flush with the upper face of the heel portion 1 of the last. The thimble 3 is of cylindrical formation open at its top and bottom and the inner wall thereof is in alignment with that portion of the wall of the opening 2 which is disposed below the lower end of the thimble. The heel portion 1 of the last is tapered upwardly and has secured to its upper face a resilient pad 7 which is formed with an opening 8 extending therethrough. With the pad 7 in position on the heel portion 1, the wall of the opening 8 is in alignment with the inner wall of the thimble and the thimble is securely held in position within the opening 2 by that portion of the pad immediately surrounding the opening 8 being seated upon the upper face of the flange 6. The pad 7 is maintained in position on the heel portion 1 of the last by means of suitable holdfast devices 9.

Secured to the lower face of the heel portion 1 of the last, by means of suitable holdfast devices 10, is a rigid reinforcing plate 11 which is formed with a preferably rectangular opening 12, the central portion of which is in alignment with the opening 2. Forwardly of the opening 12 is an opening 13 through the plate 11, into which a portion of the heel portion 1 of the last of corresponding size and shape extends. Such portion is indicated at 14 and the lower face thereof is flush with the lower face of the plate 11.

The last is positioned within the shoe with the plate 11 seated on an insole plate 15 which is secured adjacent its forward end to the insole 16 by means of suitable rivets 17. The forward inside corner 18 of the plate 15 is extended forwardly of the insole for a greater distance than the forward outside corner 19 for a purpose to be hereinafter referred to. Extending through the plate 15 is an elongated opening 20 which is adapted to be

- brought into alignment with the opening 13 through the plate 11 when the plates 11 and 15 are in assembled relation. The insole may be fastened to the last by means of a suitable tack 21 driven through the insole and through the openings 20 and 13 into the last. Rearwardly of the opening 20 the plate 15 is formed with a countersunk circular opening 22 which is in registry with the openings 12 and 2 of the plate 11 and heel portion 1 of the last. The insole 16 is seated on the upper face of the outsole 23 of the shoe. 75
- To attach a heel such as 24 to the shoe, the heel is placed in position against the lower face of the outsole 23 and a relatively small drilling bit, not shown, is inserted through the opening 8, thimble 3, lower portion of the opening 2 and through the openings 12 and 22 and a hole is bored through the insole 16, outsole 23, and into the heel 24. The drilling bit is then removed and a screw such as 25 is inserted through the thimble and opening 2. 80
- Before positioning the heel against the heel seat portion of the outsole, an adhesive substance is interposed between the heel and heel seat. The adhesive substance may be applied either to the heel or the heel seat, or both. The screw 25 is of greater diameter than the hole which has been bored through the soles 16 and 23 and into the heel 24 and when the screw 25 is tightened the heel will be securely held in position whereby further operations in the manufacture of the shoe 95
- may be performed during the period required for the setting of the adhesive substance. Due to the rigid plate 15 secured to the insole, the insole, outsole, and upper of the shoe are drawn firmly against the entire upper face of the heel 24 by the action of the screw 25. Due to the forwardly projecting inside forward corner 18 of the plate 15, the insole and outsole at the inside breast are pulled into position and firmly secured. 100
- While the insole plate 15 is herein illustrated and described as being seated on the insole 16, which is the preferred manner of positioning the same, it is to be understood that the plate might be otherwise positioned without departing from the spirit of the invention, such as, for instance, inserting the plate within a split portion of an insole. 110
- What we claim is:
- In an apparatus for attaching wood heels to shoes, a last formed with an opening extending vertically therethrough, a thimble seated in the upper portion of said opening and formed with an open top and bottom, and a reinforcing plate secured to the lower face of the last and formed with an opening in registry with the opening in said last to provide an unobstructed opening through said last and plate, said plate further being formed with an opening having a portion of 120
- the last of corresponding size and shape extending therethrough. 125
- In testimony whereof, we affix our signatures hereto. 130
